UNITED STATES PATENT OFFICE.

GUGLIELMO GIOVANNONI, OF TURIN, ITALY, ASSIGNOR TO OTTORINO POMILIO, OF NEW YORK, N. Y.

SWITCH FOR CONTROLLING IGNITION AND STARTING CIRCUITS IN EXPLOSION ENGINES.

1,414,734.

Specification of Letters Patent.

Patented May 2, 1922.

Application filed December 19, 1918. Serial No. 267,452.

To all whom it may concern:

Be it known that I, GUGLIELMO GIOVANNONI, subject of the King of Italy, and resident of Turin, Italy, have invented certain new and useful Improvements in Switches for Controlling Ignition and Starting Circuits in Explosion Engines, of which the following is a specification.

It is known that in explosion engines having a plurality of cylinders and provided with a plurality of magnetos it is required to ascertain by tests whether any of said magnetos, and consequently the sparking plugs fed by the same, operate in due manner; to this end are at present used sets of usual switches the tests having to be made separately for each magneto by manipulating the corresponding switch.

This invention has for its object a device by means of which the several magnetos and sets of magnetos of an engine of the kind above referred to may be controlled automatically, this device having reduced weight and size with regard to the switch sets at present required, so that it may be easily located and manipulated.

The annexed drawing shows by way of example a construction of the switch according to this invention as applied to an engine provided with four magnetos; and

Figure 1 is a diagrammatic view of the connections,

Figure 2 is the outer front view of the switch;

Figure 3 is the front view of the stationary plate provided with the contacting plugs;

Figure 4 is the central section of the cover with the cooperating handle and parts;

Figure 5 is the front view of the contacting member, and

Figure 6 is the reversed view of the same.

As shown in Figure 1, the four magnetos I, II, III, and IV of the engine are connected by means of wires 23, 24, 25 and 26 with four terminals 17, 18, 19, 20 mounted on a stationary insulated plate or disc 3 which is also provided with a terminal 4 connected by wire 2 with one terminal of the storage battery 5 intended to supply current for starting the engine; the other terminal of said battery is connected by wire 21 with the vibrator 6, a wire 22 leading from this vibrator to one of the magneto

terminals of said plate 3 say, in the case 55 illustrated, to terminal 18 connected with the magneto II. Should it be required, owing to the power of the engine, that two magnetos come into operation on starting the engine, an auxiliary vibrator 6' may 60 be inserted in parallel on the circuit of said battery 5 and vibrator 6, said auxiliary vibrator 6' being connected by wire 21' with wire 21 and by wire 22' with a terminal 8' mounted on plate 3. 65

On said disc or plate 3 are arranged five radial sets of contact plugs (Figure 3); one of said sets comprises four contact plugs 17', 18', 19', 20' arranged along a radius O and connected each with one of said terminals 17, 18, 19, 20. The other sets, comprising respectively the contact plugs arranged along radius I, II, III, IV, are formed each by three contacting plugs connected with respective terminals, in each of said sets being omitted one of said plugs corresponding to a different terminal and magneto than the plug omitted in the other radial sets. The wires connecting together said plugs and terminals are shown by dotted lines in Figure 3. 75

Finally it is to be noted that, as shown in the drawing, the contact plugs of the several radial sets corresponding with the same terminal and magneto, say 17', 17''—18', 18''—19', 19''—20', 20''—, are arranged circumferentially around the centre to which said radial sets converge. 80

On said plate or disc 3 are also mounted plug 8 connected with terminal 17 leading 90 to the magneto I and plug 8'' connected with terminal 8' to which leads the wire 22' connected with the auxiliary vibrator 6'. 95

To said disc or plate 3 is secured a metal cup or cover 9 connected electrically with the engine metallic mass or body, in which is pivoted a bar 10 controlled from outside by means of a handle 11 and spindle 11' (Figure 4). Said bar 10 extends on opposite sides of spindle 11' to form two arms 100 and is provided on one of said arms with four spring knobs 12, 12', 12'', 12''' arranged radially into an insulating block 27, said knobs being connected electrically with cover 9 and thence with body by means of bar 10 and spring contact 13 sliding on the inner surface of said cover. The radial position of said knobs is such as to allow the 105

same to come into contact each with one of the plugs 17'-18'-19'-20' mounted on the plate 3.

On the opposite arm of said bar 10 are arranged two contacting knobs 14, 14' the same being insulated from the bar but connected with each other and arranged in such a position as to be adapted to come into contact with plugs 8 and 8'' of plate 3 respectively. Said bar 10 is finally provided with a spring angle arm 10' having a knob 15 this latter being arranged in such a position as to come in register with plug 4', mounted on plate 3 and connected with terminal 4, but without connecting by itself said plug 4' with body, when the bar 10 is brought along the radius R, this position of the bar 10 corresponding with the operation of all magnetos and with the normal running of the engine.

Finally the cover 9 is provided with a spring knob 16 located in front of plug 4' and provided with a stem 29 passing through the cover 9 and having a head 30; said knob 16 on being shifted down is adapted to carry its head 30 into contact with knob 15 when this latter has been brought under it by manipulating handle 11 and bar 10 to carry these latter in the position R. On shifting down said knob 16 the plug 4' is caused to communicate with body through arm 10', bar 10, contact 13 and cover 9 which is connected with body as above described. The starting circuit is thus closed, said circuit comprising body, cover 9, contact 13, bar 10, arm 10', knob 15, plug 4' and terminal 4, wire 2, battery 5, wires 21 and 21', vibrator 6', wire 22', terminal 8', plugs 8 and 8'' and knobs 14-14' bridging the same, wire 23 connected with one end of primary winding of magneto I and body to which the opposite end of this winding is connected as usual. The starting circuit is also closed in respect to magneto II as follows: wire 21, 45 vibrator 6, wire 22, terminal 18, wire 24, primary winding of magneto II and body. Thus owing to operation of vibrators 6 and 6' the primary windings of magnetos I and II are supplied with a vibratory current this latter inducing a high tension current in their secondary windings which is fed to respective sparking plugs by the respective distributors of said magnetos as usual. The spring 28 holds said knob 16 in its usual or nonoperative position shown in Figure 4.

As it may be seen in Figure 3, by carrying the bar 10, by the manipulation of its handle 11, into the position in which it is arranged along the radius O, all the magnetos are carried out of operation the windings of the same being connected with body owing to the fact that plugs 17', 18', 19' and 20', connected with terminals 17, 18, 19 and 20 and thence with the magneto windings, are in contact with their respective knobs 12''', 12''

and 12' and 12 which communicate with body through arm 10, contact 13 and cover 9, this latter being connected with body as above described.

By carrying the bar 10 into the position I the magnetos II, III and IV are out of operation their windings, terminals and plugs 18'', 19'' and 20'' being connected with body in the manner above described, whilst magneto I is in operation there being no plug connected with this magneto in the plug set located along radius 1. Likewise, by carrying the bar 10 into positions II, III and IV, one of magnetos II, III and IV is respectively held into operation the other ones being out of operation by having their windings connected with body as above described.

On the contrary, by carrying the bar 10 into position R, all the magnetos are in operation as there is no body plug along the radius R, this position corresponding to the normal running of the engine. Further in this position the circuit of auxiliary vibrator 6' is connected with magneto I, the electrically connected knobs 14-14' bridging plugs 8 and 8''. In this position of bar 10 the knob 15 is located in register with plug 4' but is removed from the same, so that by shifting knob 16, the starting circuit may be closed as above described.

By the described device, when it is required to start the engine, the handle 11 is carried in such a position as to bring bar 10 into position R and thence the knob 16 is shifted to close the starting circuit.

The engine being thus started, the operation of the magnetos and of sparking plugs connected therewith may be tested and inspected by manipulating handle 11 to carry in succession the bar 10 into position I, II, III, IV, so as to bring out of operation three of said magnetos at each time and leave into operation a different one of them, according to said position, and thus the operation of the magnetos is inspected. During this manipulation by which a number of magnetos are carried out of operation, the vibrator 6' connected in parallel with vibrator 6 is disconnected from the corresponding magneto I as the knobs 14-14' bridge the plugs 8 and 8'' leading to said magneto I and vibrator 6' respectively, only when the handle 11 is in its position by which all the magnetos are in operation whilst in any other position of said handle the plugs 8 and 8'' are disconnected.

Thus it is provided that on connecting with the body either of magnetos I or II, the other one may also be connected with body through wire 22, vibrator 6, wire 21, vibrator 6', wire 22' and either of corresponding plugs and terminals 17 and 18 to which lead the wires 23 and 24 connected with said magnetos, as it could happen should wire 22' be permanently connected with terminal 17.

Thus no particular manipulation for disconnecting the auxiliary vibrator from its own magneto as it is necessary with the devices at present used to the end of preventing this latter magneto from being connected with body when the magneto to which the other vibrator is connected is caused to communicate with the body.

The device according to this invention provides within a reduced space all the parts required for controlling and testing the operation of several magnetos of the same engine and allows of effecting the required manipulations in a very easy and quick manner.

What I claim as my invention and desire to secure by United States Letters Patent is:

1. A system for controlling ignition and starting circuits in explosive engines comprising, a plurality of magnetos, a starting circuit including a main vibrator and an auxiliary vibrator, the latter adapted to be used when required by the power of the engine, a storage battery in the said starting circuit, a switch having a number of contacting parts arranged in a plurality of sets, means for connecting the contacting parts of each set with one of the magnetos, means for short-circuiting any required set to put the magnetos connected therewith out of operation, means for connecting a magneto for each vibrator used with one terminal of the starting circuit, means for closing the current through a connection with the other terminal of the starting current circuit, when said sets of contacts will be excluded from the circuit.

2. A system for controlling ignition and starting circuits in explosive engines comprising, a plurality of magnetos, a starting circuit including a main vibrator and an auxiliary vibrator, the latter adapted to be used when required by the power of the engine, a storage battery in the said starting circuit, a switch having a number of contacting parts arranged in a plurality of sets, means for connecting the contacting parts of each set with one of the magnetos, means for short-circuiting any required set to put the magnetos connected therewith out of operation, means for connecting a magneto for each vibrator used with one terminal of the starting circuit, means for closing the current through a connection with the other terminal of the starting current circuit, when said sets of contacts will be excluded from the circuit, and means to exclude the starting circuit when any set of contacts is connected in the circuit.

3. A system for controlling ignition and starting circuits in explosive engines comprising, a plurality of magnetos, a starting circuit including a main vibrator and an auxiliary vibrator, the latter adapted to be

used when required by the power of the engine, a storage battery in the said starting circuit, a switch having a number of contacting parts arranged in a plurality of sets, means for connecting the contacting parts of each set with one of the magnetos, means for short-circuiting any required set to put the magnetos connected therewith out of operation, means for connecting a magneto for each vibrator used with one terminal of the starting circuit, means for closing the current through a connection with the other terminal of the starting current circuit, when said sets of contacts will be excluded from the circuit, means to exclude the starting circuit when any set of contacts is connected in the circuit, and means for excluding the starting circuit and including all said magnetos in the circuit for normal operation of the engine.

4. A system for controlling ignition and starting circuits in explosive engines comprising, a plurality of magnetos, a starting circuit including a main vibrator and an auxiliary vibrator arranged in parallel with the main vibrator, the auxiliary vibrator adapted to be used when required by the power of the engine, a storage battery in the said starting circuit, a switch having a number of contacting parts arranged in a plurality of sets, means for connecting the contacting parts of each set with one of the magnetos, means for short-circuiting any required set to put the magnetos connected therewith out of operation, means for connecting a magneto for each vibrator used with one terminal of the starting circuit, means for closing the current through a connection with the other terminal of the starting current circuit, when said sets of contacts will be excluded from the circuit.

5. A system for controlling ignition and starting circuits in explosive engines comprising a plurality of magnetos, an insulated base support, a switch on the support having a plurality of contacting parts arranged in groups radially arranged with respect to the support, each group adapted to include individually a different magneto in the circuit, an arm mounted upon the support carrying at one end contact plugs adapted to contact with the said contacting parts, said arm provided at the other end with other contact plugs, other contact parts arranged upon the said base for contacting with the last mentioned contact plugs for effecting the starting circuit with an auxiliary vibrator, an extension mounted upon the said arm and at an angle thereto, a movable plug slidably mounted upon the support and adapted to become electrically connected with the said extension.

Signed at Turin, Italy, this 11th day of October, A. D. 1918.

GUGLIELMO GIOVANNONI.
